(57) **CLAIM**

The ornamental design for a shoe, as shown and described.

DESCRIPTION

FIG. 1 is a bottom rear perspective view of a shoe showing our new design;

FIG. 2 is a bottom view thereof; and,

FIG. 3 is a bottom front perspective view thereof.

The broken line immediately adjacent to and surrounding the shaded area defines the peripheral bounds of the claimed design and forms no part thereof. The spaced apart parallel broken lines within the shaded area form no part of the claimed design. The broken lines depicting the remainder of the shoe form no part of the claimed design.
